COUPLING MECHANISM

Filed July 11, 1929

UNITED STATES PATENT OFFICE

CHARLES H. TOMLINSON, OF MANSFIELD, OHIO, ASSIGNOR TO THE TOMLINSON COUPLER COMPANY, OF MANSFIELD, OHIO, A CORPORATION OF OHIO

COUPLING MECHANISM

Application filed July 11, 1929. Serial No. 377,473.

My invention relates to car, air and electric coupling mechanism for joining the ends of cars in a train, and one of the objects is to provide such coupling mechanism which will 5 minimize the errors in operation due to the human element.

Another object is to provide means for compelling the correct operation of the coupling mechanism by the trainmen.

10 Another object is to provide means for requiring the coupling mechanism to be properly connected and all valves and switches properly arranged before the train can be moved.

15 Another object of my invention is to provide means for controlling the air and electric coupling mechanism on two coupled cars from a station in either of the cars.

Another object of my invention is to provide 20 a car, air and electric coupling system which can be coupled to another car equipped with an ordinary car and air coupling system and which will still require proper operation of the controlling means for the car, air and 25 electric coupling means before the train can be moved.

The invention is set forth in the combination and arrangement of parts shown in the 30 accompanying drawing and described in the following specification, and is particularly set forth in the claims.

In the drawing:—

Fig. 1 is a somewhat schematic or diagrammatic view of my coupling system as applied 35 to one end of two coupled cars and shows the car, electric and air coupling mechanism as suspended below the platform of the car A. The controlling parts may be located wholly or partially below or above the car floor.

40 Fig. 2 is a horizontal sectional view of my coupler head showing the knuckle or coupling hook in uncoupled position.

Fig. 3 is a horizontal sectional view of a 45 portion of the coupler head showing the knuckle or hook in position as when coupled.

Fig. 4 is a front view in elevation of my car, air and electric coupler heads.

Fig. 5 is a horizontal sectional view of the 50 mechanism which I employ to move the knuckles to their open position and also to

permit the escape of air from the brake lines and set the brakes to prevent moving the cars unless the coupling of the cars has been properly completed.

In order to safely operate a train of cars, it 55 is of utmost importance that the air brake line and train line circuits shall be properly connected and especially the air brake line to provide communication throughout the entire train from the engineer's cab. The automatic air brake line is usually provided with a cutout or angle cock at each end of each car intended to be manually operated when two cars are coupled or uncoupled, and it is of 60 vital importance that these valves be opened to insure proper operation of the brakes on a train, for if a single valve is left closed, the engineer is powerless to apply the air brakes on these cars beyond the closed valve.

It is quite usual after a passenger train 65 has been made up for the engineer to apply the brakes and for the attendants to examine the brakes and see if they operate properly. If one of the cutout cocks is left closed at any place in the train and the attendant 70 should fail to note that the brakes do not operate and signals the engineer to the effect that the brakes are operating properly, there is nothing to warn the engineer that the attendant has failed in his duties and that he 75 will be unable to properly apply his brakes throughout the train, until he attempts to do so after starting the train. If, then, the brakes fail to operate, the engineer will sense 80 something is wrong but it may then be too late to avoid an accident. A single cutout cock in the brake line left closed after the train is in operation may cause a disastrous 85 wreck.

My present invention provides means for 90 setting the brakes if any one of the cutout cocks in the brake line is left closed after the train has been coupled and ready to move, or if any one of the cocks should in some 95 manner become closed while the train is in motion or after it has been in proper operation. Further, if the train is equipped with electric train line circuits, my invention compels these circuits to be connected from car to car in proper relation simultaneously with 100

the proper connecting up of the brake line circuit.

Also, I may connect a car equipped with my invention and having air pressure thereon to a like equipped car and not having pressure and still compel the proper setting of the brake valves and the switches before the train can be moved.

In Fig. 1, I have indicated two cars A and B as coupled mechanically, electrically and pneumatically and the coupled devices meeting on the center line $x-x$. The equipment shown on car A schematically is duplicated on car B.

15 The car platform has secured thereto an anchorage 2 to which is secured the car coupling mechanism 3 and supported by a bracket to permit the coupler to swing radially about the universal joint at 2. Securely mounted below the coupler 3 is an electric and pneumatic coupler 4.

20 The car coupler comprises a body member 5 having a recess 6 and a projection 7 to co-operate with recesses and projections on the 25 coupled head to prevent relative movements of the coupled head other than in a longitudinal direction. Each head is also provided with a coupler knuckle 8 shown as that of the Janney type, although other types of 30 knuckles or hooks may be employed. The knuckle is held in the open and closed position by a sliding lock 9 constantly urged to its locking position by the spring 10. The 35 lock may be moved to disengage the knuckle 8 by means of the pull chain and handle 11; also, means 12 is provided for pneumatically and automatically moving the locks on both 40 coupled cars to their uncoupled positions respectively by an attendant from a station in either car.

The knuckle 8 when released from the lock 9 is moved to its open or unlocking position by means of a combined spring operated pin and valve mechanism 13, shown more in 45 detail in Fig. 5.

When two of my coupler heads are brought together both knuckles will be in the unlocked position as shown in Fig. 2 and co-operation will be secured to move both 50 knuckles to the locked position shown in Fig. 3, thereby preventing the longitudinal movement of the coupler heads relative to each other. The engaging surfaces of the knuckle 8 and lock 9 are wedge shaped, thus permitting 55 the knuckles to draw the faces of the heads into close relation and maintain them tightly locked, thus producing a substantially rigid coupling between cars, as set forth in United States Letters Patent 1,660,733 issued February 28, 1928.

60 Mounted below the coupler 3 is an air and electric coupler 4 provided on its center vertical line with the butt end pneumatic coupler 14 for the brake line and 15 for the 65 reservoir air line. The connector 15 is pro-

vided with a check in the face which opens upon impact of two similarly equipped cars, but closes automatically when uncoupled.

The head 4 is also provided with contacts 16 and 16', 17 and 18, 19 and 19', 20 and 20', 70 and others. When it is desired to couple like electric circuits between cars, regardless of which end of the cars are coupled, I find it 75 advisable to connect such circuit to two contacts placed in the same horizontal plane and equally spaced from the vertical center line, as, for instance, cross-connected contacts 16-16', 19-19', 20-20'. Fig. 1 shows contacts 16-16' cross-connected as explained.

The train line circuits 19 and 20 shown in 80 Fig. 1 would be extending to the coupler head 4 and connected to the contacts 19-19' and to contacts 20-20' respectively. I am using the contacts 16-16', 17 and 18 for control circuits, as later explained.

85 My invention involves also a brake line 21 open to the atmosphere when unconnected at the connector 14 and controlled by a cut-out valve 22. In order that the brakes on two coupled cars may properly operate, it is necessary for the valve 22 to be in an open position and my invention relates largely to 90 means of compelling the valve 22 to be opened before the train can be moved. If air in the line 21 is allowed to escape to atmosphere 95 at any point, it will automatically cause the brakes to set, thus preventing the moving of the train.

100 Leading from the pipe 21 is a branch pipe 23 which is controlled by a supplemented plug valve 24, and the plug is arranged with two ports opened or closed simultaneously, one of which controls the pipe 23, while the other controls a pipe leading to the uncoupling mechanism 12, as later described. Leading 105 from the branch pipe 23 is another branch pipe 25 leading to the mechanism 13, which has a valve for controlling the pipe 25 and a spring held pin for urging the knuckle 8 to its open position.

110 The mechanism 13 (Fig. 5) comprises a cylinder 26, a screw cap 27, fastening lug 28, spring pressed plunger 29, having grooves 30 to permit the escape of air, spring 31 urging the pin 29 forward, an auxiliary valve and stem 32 closing a chamber 33 from the chamber 34 by engaging the seat 35 and held against the seat by the spring 36. The pin 29 is moved inwardly when the knuckle is 115 in its closed position and after moving a pre-determined amount, engages the end of the valve 32, causing the same to open and remain open as long as the knuckle is in its closed position, thus allowing air from the pipe 25, which is connected with the chamber 120 33, to escape to the atmosphere, and as pipe 25 receives air from the brake line 21, the 125 brakes will automatically set as the valve 35 is open and air is escaping from the mechanism 13.

Connected on the end of the pipe 23 is the ordinary hose pipe and coupling 37 and this will be found convenient when coupling a car equipped with my invention to a car of the standard type of air equipment having a hose coupling.

If the hose coupling 37 is employed, I insert a valve 38 to control the flow of air such that the valve will allow air to flow from 23 to 37, or from 23 to 25. The valves 22 and 24 are interlocked for simultaneous operation through the medium of the shafts on the switches 39 and 40, and the pneumatic engine 41 and the ports are so arranged that when valve 22 is open, and the valve 24 closed, the switches will be closed or vice versa.

If the electric switches are not employed, the valves 22 and 24 are directly connected together for simultaneous operation either by the engine 41 or the manually operated handle 42.

The operation of the brake system is as follows:

If two cars A and B equipped alike are coupled, the angle cocks 22 on both cars would be closed if air pressure were present, otherwise the escape of air at the connector 14 would set the brakes and prevent moving the cars into coupled relation. Also, the valve 24 would be open and air would flow through to the mechanism 13, but could not pass the valve 32 as it would be closed by the spring 31 which moves the pin 29 to its forward position, the coupling knuckle 35 being held out of the path of the pin 29 by lock 9. The valve 38, it will be apparent, would be connected to communicate pipe 23 with 25, otherwise if it was set to communicate 23 and 37, there would be an escape of air through the hose 37 to atmosphere, thus preventing the moving of one or both cars to coupled relation.

Simultaneously with the coupling of cars, the knuckles 8 would be moved to their closed position, shown in Fig. 3, which would retract the pin 29, causing it to engage and open the valve 32 and thus permit the escape of air from the pipe 25 to atmosphere, which would apply the brakes automatically and would indicate by the sound of escaping air that the valves of the brake system were not in proper position. The attendant would then open the valve 22 either by means of the handle 42 or through the medium of the pneumatic engine 41, later explained, and simultaneously close the valve 24, thus checking the flow of air through the mechanism 13 and restoring the brake valves to proper condition for operation, and also closing the switches 39 and 40 controlling the electric circuits.

If the car A is coupled to a car having the ordinary car and air equipment, then the hose 37 of the car A would be connected to the corresponding hose of the coupled car and

as the valve 38 would probably be set to communicate pipe 23 with 25, there would be an escape of air at the coupler head of car A at the instant of coupling, as the valve in pipe 23 would be open and the attendant would then operate the valve 38 to communicate pipe 23 with hose 37. In this case, valve 22 would remain closed and the valve 24 would remain open and no air would escape from the connector 14, also the switches 39 and 40 would remain open as there would be no need of these switches closing when coupled to an ordinary equipped car.

It is possible that the car equipped with my invention and having air pressure thereon is coupled to a car similarly equipped but having no air pressure thereon and in that case it would be apparent that if the valve 22 were closed, that air would flow from the coupled car through to the valve 22 but no further, and there would be no escape of air at the coupler head through the mechanism 13 on the car without pressure and, therefore, there would be no positive way of indicating to the attendant that the valve 22 on that car was closed. Therefore I place about the valve 22 a check valve 43 which will permit air to flow in the direction of the arrow but not in the other direction. Air will then flow from the coupled car through the pipe 21, through the check valve 43 to the pipe 21 on the opposite side of the valve 22 and then will flow through the pipes 23 and 25 and escape at the coupler head, thus setting the brakes and preventing movement of the train until the attendant has opened the valve 22 and simultaneously closed the valve 24 on the car without pressure.

The same is true if the car A had no air and was coupled to an ordinary equipped car having air, that is, the valve 38 being set to connect 23 and 25, would prevent the flow of air from the coupled car through the car A, which possessed no air. Therefore, I place about the valves 38 and 24 a by-pass containing check valves 44 and 45 respectively and which permit the flow of air in the direction of the arrows, thus air will flow from the ordinary equipped car having air pressure, through the hose 37, by-pass and check 44, into the pipes 23 and 25 and escape at 13, and if the valve 24 is closed air will also by-pass through 45 and escape at 14, thus setting the brakes, or if the valve 38 connects pipe 23 with hose 37 and the valve 24 is closed, then the air will bypass at 45 and enter pipe 21 and escape at 14 as valve 22 will be open, thus compelling the closing of valve 22.

My invention involves the manual operation of the valves and switches by the handle 42 or pneumatic operation by means of the air engine 41, which comprises a cylinder with a reciprocating piston therein which moves the shaft 46 connecting the switches and angle cocks. Connected to one end of the

piston is a pipe 47 and to the other end a pipe 48. These pipes are controlled by electro pneumatic valves of any approved type, 49 and 50. Air is supplied to the valves 49 and 50 through the pipe 51 connected to the reservoir air line 52.

In order to operate electro pneumatic valves, I have provided a system of circuits controlled by push button switches and indicated as 53 for the "on" switch and 54 for the "off" switch. The control circuits between the cars are connected by the electric contacts 16-16', 17 and 18. As I am desirous of always connecting the conductor 55 on one car with conductor 55' on the other car, I use the double contacts 16-16' positioned as shown in Fig. 4, but as it is immaterial whether conductor 56 and conductor 57 of one car connect with like or opposite conductors on the other car, I merely use single contacts 17 and 18.

To each switch is brought a source of current supply 58 and the switches 53 and 54 are normally held out of contact with the source of supply. From the conductor 57, a branch 57' extends to the valve 49 and from the conductor 55, a branch 55' extends to the valve 50.

I have shown the switch 53 in car B as closed, which would be the condition if the attendant on that car, after the cars have coupled by impact, is desirous of operating the valves 22 and 24 and the switches 39 and 40 to their proper running positions on both cars. In this case, after the cars have coupled the operator presses the switch 53 and current flows from 58 through the conductor 56, contacts 18-17, conductors 57 and 57' to valve 49 on car A and also through switch 53 in car A and conductor 56, contacts 18-17 and conductors 57 and 57', thus energizing the valve 49 on car B and permitting air to flow through the pipes 47 to the engines 41 on both cars, thus moving the switches to their closed position and the valves 22 to their open position and the valve 24 to its closed position. The operator then releases the switch 53 on car B and the coupled cars are then in operated condition.

It will be noted that if car A is the rear end car and if an unauthorized person closed switch 53 in car A that the valve 49 on car A would not operate to close the switches 39 and 40 and open the air valve 22. This is due to the method of connecting switches 53 and valve 49.

If the attendant is desirous of disconnecting the cars, he will close the switch 54 on car B after he is there located and current will then flow from the source 58, through the switch 54, conductor 55, 55', contacts 16-16', conductors 55 and 55' to valves 50 on both cars, thus energizing the valves 50 and permitting air to flow through the pipes 48 on both cars to the cylinder 41, thus moving the

switches to their open position and closing valve 22 and opening valve 24. The attendant then permits switch 54 to open.

The pneumatic uncoupling engine 12 comprising a cylinder and piston therein, which is connected to the lock 9, is operated through the medium of air pressure delivered thereto through the pipe 59 connected to the pipe 48 and controlled by one of the ports in the valve 24, which is open when the other port 75 in valve 24 controlling pipe 23 is open. Thus when the switch 54 in either car is operated and the valves 50 in both cars opened, air flows through the pipes 48 to cylinders 41 and also flows through the pipe 59 to the engine 80 12, providing the valve 24 is open.

Attention is drawn to the fact that when two cars equipped alike with my invention are coupled and operating, that valve 22 in each car will be open and valve 24 will be closed. Therefore, when the switch 54 in either car is closed, it will be evident that air must first flow through the pipe 48 into engine 41 and move the switch to the open position and the valve 22 to its closed position before air can flow through the valve 24 to the uncoupling engine 12, because the valve 24 is closed until the switch opens and the valve 22 closes. This insures the impossibility of uncoupling or separating the cars until the 95 switches and the valves 22 and 24 are properly set.

It will be evident that whether the coupler system shown in connection with car A is connected with a car equipped with a like system 100 or with a car equipped with the ordinary flexible hose connection, it will be impossible to operate the train until proper communication between the air lines of the two cars has been established, and if one or both of the 105 cars are equipped with electric connectors, the switch controlling the same must be in proper position. It is further evident that if two cars equipped alike with my invention should be coupled and only one provided with 110 air pressure, that air will flow from the car possessing pressure to the other car, thus establishing pressure therein and compelling proper manipulation of the valves and switches before the train can be moved; also, if a car equipped with the ordinary hose is connected to a car equipped with my invention and which does not have pressure thereon, air will flow from the ordinary equipped car to the car equipped with my invention, 115 thus establishing pressure thereon and maintaining the safety feature described.

If it is desired to separate two coupled cars by manual operation of the car coupling mechanism, the operator will pull the chain 125 11 on that car which he desires to move. This will open the knuckle 8 on that car and permit the valve 32 to close against the seat 35 and thus prevent the escape of air and the setting of the brakes.

There will, of course, be many modifications to my invention which will be evident to those skilled in the art after making this disclosure, and, therefore, I wish to be limited only by 5 my claims.

I claim:—

1. The combination with coupled cars having brake lines and connectors therefor, of means mechanically coupling the cars, cut-out valves for the brake lines, an auxiliary valve connected with the brake line of one of said cars and having an outlet port to atmosphere of sufficient capacity to set the brakes of the cars, means to operate said auxiliary valve to open position upon bringing together of the cars to connect the brake lines to atmosphere, means to operate the said cut-out valves, a supplemental valve for closing the connection between said auxiliary valve 10 and its brake line when the cut-out valve in said brake line is open and means to control the operation of the said cut-out valve operating means on two coupled cars by an operator from a station on either car.
2. The combination with coupled cars having brake lines and connectors therefor, of means for mechanically coupling the cars, a cut-out valve for a brake line, a branch from the brake line connected to atmosphere, a supplemental valve for closing said branch when said cut-out valve is open and opening said branch when said cut-out valve is closed, auxiliary valvular means and means to operate the same opened upon the coming together 15 of two cars to control the branch line and close the branch when the cars are uncoupled, a check controlling a bypass around the cut-out valve and a check controlling a bypass around the supplemental valve in the branch line and the said checks operating to permit air under pressure to pass through said bypasses only from a coupled car.
3. The combination with coupled cars having brake lines and connectors therefor, of means for mechanically coupling the cars, a cut-out valve for a brake line, a branch from the brake line connected to atmosphere, a supplemental valve for closing said branch when said cut-out valve is open and opening 20 said branch when said cut-out valve is closed, an auxiliary valve in said branch and means to open said auxiliary valve upon the coming together of two cars and to close said auxiliary valve when the cars are uncoupled and means to admit air to the brake line past said cut-out valve from a coupled car in case said brake line is not already charged with air.
4. In combination a car, a mechanical coupler, a brake line, a cut-out valve to control the brake line, means to connect the brake line to that of a coupled car, a branch from the brake line having an auxiliary valve therein and means to open the auxiliary valve 25 on coupling to another car to allow escape of air from the brake line and means to conduct air around said cut-out valve when closed to charge said brake line from a coupled car, said air escaping through said branch pipe and auxiliary valve and a supplemental valve in the branch line to close the branch line when the cut-out valve in the brake line is opened and prevent the escape of air from the branch line.
5. The combination of two coupled cars each having a brake line and connector therefor, means for mechanically coupling the cars, a cut-out valve for closing the brake line, a branch from the brake line, a supplemental valve for the branch, the valves being connected to close one valve when the other valve is opened and vice versa, a pneumatic engine to operate the valves, means on both cars under control of an operator from a station in either car to operate the pneumatic engine on both cars and an auxiliary valve for the branch line operable to its open position when two cars are coupled to permit the escape of air from the brake line when the cut-out valve in the brake line is closed.
6. The combination with a brake line for a car and means for connecting said line with the brake line of a coupled car, of a cut-out valve for closing said brake line, a car coupler, an auxiliary valve connected with said brake line and operable by the movement of the coupler in coupling to another car to open and allow escape of air from the brake line and held open while the cars are coupled, and a supplemental valve connected with said auxiliary valve to permit the said escape of air through said auxiliary valve when the cut-out valve is closed and means providing for the flow of air from one coupled car to the brake line of the other car when the cut-out valve in said other coupled car is closed.
7. A system of train line coupling devices on two cooperating cars, comprising a fluid pressure line having connection through the couplers, valve mechanism in each car to control said line and means for opening and closing said valve mechanism on both cars from a station on one car, and means to open said fluid pressure line to the atmosphere upon the bringing together of the cars in coupled relation to bleed the air from the fluid pressure line sufficiently to set the brakes of the cars when said valve mechanism is closed, said opening means being operable to maintain open connection between said fluid pressure line and atmosphere so long as said cars are coupled and said valve mechanism is closed.
8. The combination with a car of an air brake line for said car, separate means for connecting said air brake line with the air brake line of a coupled car, one means connecting automatically upon impact and the other means connecting manually after impact, a cut-out valve controlling the auto-

matic connector, a three-way valve for closing the air brake line to manual connecting means and for opening the air brake line to a branch line, an auxiliary valve for opening the branch line to atmosphere by the bringing together of the cars, a supplemental valve to control the line to the manual connection and operable in unison with the cut-out valve to open when the cut-out valve closes and means to conduct air from one car to the other past the three-way valve, the cut-out valve and the supplemental valve when said valves are closed.

9. In a car and pneumatic coupling system on two coupled cars each having a car coupler, an air brake line having a valve therein to control the line and a coupling device, a pneumatic engine to operate the valve and means on each car to control the operation of the engine on both cars at will of an operator from a station on either car, an air engine to move the car coupler mechanism to uncoupling position, a piping system connecting the air coupling device, the uncoupling engine, the valve actuating engine and the control means for the valve actuating engine, to operate the valve actuating engine to close the valve in the brake line on each car before air is admitted to the uncoupling engine on each car, and means to open the brake line to atmosphere to set the brakes when the said valves are closed.

10. The combination with a plurality of electric train line circuits, of a switch for controlling said circuits, fluid pressure pipes for a brake system, valves controlling the pipes and arranged to operate in unison with each other and the switch and to open and close in reverse relation to each other, fluid pressure operated means to move the valves and switches to control communication through the pipes and circuits, auxiliary valvular means opened upon the coming together of two cars to open the brake system to atmosphere when one of the valves is open and the other closed and the switch open, and manually operated means controlling the fluid pressure for actuating the fluid pressure controlled means.

11. The combination of a car, an electric train line circuit, and a connector therefor, a brake line and a connector therefor, a switch to control the circuit, a cut-out valve to control the brake line, means to open or close the switch, car coupling means, means forming a passage from said brake line to atmosphere, valvular means for closing said passage but operated by the car coupler to open position when two cars are coupled and the switch is opened, and a supplemental valve in said passage constrained to act in synchronism with said switch to prevent the escape of air through said passage when the switch is closed.

12. The combination with cars having

brake lines and brake line connectors, of means for mechanically coupling said cars, a valve for closing the brake lines, a connection from said brake line and valvular means controlled by the mechanical coupling means for opening said connection to atmosphere, said valvular means comprising a spring closed valve and a plunger held spaced from said valve by a spring and engaging the valve to open the same after the plunger has been engaged and moved by a part of the coupler.

13. A car coupler comprising a head and coupling hook, a lock to hold the hook in coupled position, a reciprocating spring held plunger engaged by and moved by the hook, a valve normally held closed by a spring and arranged to be opened by the movement of the plunger under action of the hook, the plunger tending to move the hook towards its uncoupled position and release the valve from its open position to close.

14. A car coupler comprising a head and coupling hook, a lock to hold the hook in coupled position, a reciprocating spring held member engaged by and moved by the hook, a valve member spaced from the reciprocating member and normally held closed and arranged to be opened by the movement of the reciprocating member, the reciprocating member moving a predetermined amount before it opens the valve.

15. The combination with a car having a brake line and a valve for closing said brake line, of a coupler for said car having a coupling knuckle, controlled means for bleeding said brake line, a valve for closing said bleeding means and common means for opening said valve and actuating said coupling knuckle.

16. The combination with a car having a brake line and a valve for closing said brake line, of a branch pipe leading from said brake line at the car side of said valve, an auxiliary valve for closing said branch pipe, a coupling knuckle, and common means for opening said coupling knuckle and closing said auxiliary valve.

17. The combination with a car having a brake line and a valve for closing said line, of a branch pipe connected with said brake line at the car side of said valve, a coupler for said car having a coupling knuckle, a plunger for opening said coupling knuckle, an auxiliary valve for closing said branch pipe, said auxiliary valve being connected with said plunger and opened by said plunger when said knuckle is closed.

18. The combination with a car having a brake line, a cut-out valve for closing said brake line, a one-way by-pass about said cut-out valve, a branch pipe connected with said brake line at the car side of said cut-out valve, a second valve for closing said branch pipe, means connecting said cut-out valve and said second valve to open one of said valves when

the other is closed and vice versa, a one-way
by-pass about said second valve, a coupler
for said car having a knuckle, a lock for hold-
ing said knuckle closed, a plunger for open-
ing said knuckle when unlocked, and an aux-
iliary valve controlled by said plunger for
closing said by-pass when said knuckle is
opened.

5 In testimony whereof I affix my signature.
